UNITED STATES PATENT OFFICE.

CHARLES C. THOMAS, OF DETROIT, MICHIGAN, ASSIGNOR TO COPELAND PRODUCTS, INC., OF DETROIT, MICHIGAN, A CORPORATION OF MICHIGAN.

DESIGN FOR A REFRIGERATOR CABINET.

Application filed April 3, 1926. Serial No. 17,177. Term of patent 14 years.

To all whom it may concern:

Be it known that I, CHARLES C. THOMAS, a citizen of the United States, residing at Detroit, in the county of Wayne and State of Michigan, have invented a new, original, and ornamental Design for Refrigerator Cabinet, of which the following is a specification, reference being had to the accom-

panying drawing, forming a part thereof, in which the single figure is a perspective view of the article showing my new design.

I claim:

The ornamental design for a refrigerator cabinet, as shown.

CHARLES C. THOMAS.
